UNITED STATES PATENT OFFICE.

HARRISON D. STERRICK, OF PITTSBURGH, PENNSYLVANIA.

PICTURE GLASS AND MOUNT.

1,032,515.

Specification of Letters Patent. Patented July 16, 1912.

Application filed January 28, 1909. Serial No. 474,686.

To all whom it may concern:

Be it known that I, HARRISON D. STERRICK, a citizen of the United States, residing at Pittsburgh, in the State of Pennsylvania, have invented a certain new and useful Picture Glass and Mount, of which the following is a specification.

My invention relates to mountings for photographs, advertisements, and the like, 10 and its primary object is to provide a combined picture mount and glass giving the picture the appearance of a medallion with an ornamental frame, the whole being made in one piece of glass. I have illustrated the 15 mechanical construction in one form, in the accompanying drawing, wherein—

Fig. 1 is a back elevation and Figs. 2 and 3 are respectively a vertical, and a horizontal, section.

20 In my device I combine two very desirable features of ornamental picture mounting, to wit, the medallion or embossed appearance, and the rich metallic frame, or back ground, with great simplicity and 25 cheapness, and at the same time provide a support for the ornamentation and a frame for the picture.

The paper having the picture may not be bent much out of a plane, but by giving the 30 glass a lens form the effect is to make the picture appear as highly raised. The entire effect and appearance of a carved metallic frame is given by properly forming the surface of the glass to reflect the light, 35 and then painting thereon a metallic paint, the glass giving the paint surface in contact a polished appearance. In the drawings, as an example I show my invention as a 40 mount made in a general rectangular form with an oval center 4, which may be concave or convexed outwardly to form a lens, and integral with this center and the space 45 for ornament is a surrounding and depending flange 5. Surrounding the space 4 for reception of the picture I place several series 50 of ornamental beads or indentations 6 and 7 and outside of this the remainder of the rectangular space is filled with any embossed ornamentation 9, and along the inner side 55 of the flange 5 are striated parts 8. I prefer to cover the whole surface except the picture space, with metallic paint as represented at 10, and other ornamentation such as metal chips and pieces of mother-of-pearl 60 11 are cemented on in the space between the ridges 6 and 7. When looked at from the

front side this construction gives the appearance of a heavy carved metal frame surrounding a glass over an embossed picture. Of course the form may be indefinitely 60 changed and the character of metallic paint and any other ornamentation on the back of the glass may be of various designs and colors, and I am not limited to any materials. I have however, produced most 65 pleasing effects by covering the back of the glass with ordinary gold paint and using mother-of-pearl for the parts 11, and filling the spaces between the pieces with a coarse 70 grain metallic paint 12, which gives this 75 whole surface the appearance of being inlaid.

I am aware that molded picture frames are not new, but I believe I am the first to provide a molded picture glass with its rear 75 surface embossed so that paint placed thereon will appear with a glossy surface on the front side. Moreover, it will be observed that the several spaces for receiving the metallic paint are separated by ridges or depressions making sharp divisions, and this I believe to be broadly new. By this means the application of the paint with a brush is perfectly easy and requires no skill.

Though the device can be used with an 80 extra frame, it is itself both a frame and a covering glass for the picture. The pasting or cementing of a picture directly on the glass moreover prevents the entry of dust and dirt on the picture surface, while the 85 metallic paint of course being in contact with the glass and not exposed to the air cannot become dirty or tarnished. In addition, the hollow back allows of pouring 90 in a solid sealing composition for better 95 preservation of the picture and ornamentation.

Having thus described my invention and 100 illustrated its use, what I claim as new and desire to secure by Letters Patent, is the following:

1. A combined picture frame and mount, comprising in one integral piece a lens having a recess on the back for pasting a picture thereon, a surrounding border embossed 105 on the back, and ornamental figures to represent a frame and border, said figures being depressed in the back of the article and the depressed surfaces separated by ribs and being covered by metallic paint, substantially as described.

2. A combined picture glass and frame

comprising a lens having, molded integrally therewith, a flange representing a frame for a picture pasted on the back of the lens, the back of said frame portion being hollow to 5 protect the picture and ornamentation, and being provided on its surface with embossed ornamentation covered with paint on the surfaces thereof, said ornamented surface being divided into spaces for easy 10 application of the paint by division lines of

sharp angles, between the surfaces, substantially as described.

In testimony whereof, I have hereunto signed my name in the presence of the subscribed witnesses.

HARRISON D. STERRICK.
